UNITED STATES PATENT OFFICE.

FRED HAUERWAS, OF ROCK ISLAND, ILLINOIS, ASSIGNOR TO MOLINE IRON WORKS, OF MOLINE, ILLINOIS, A CORPORATION OF ILLINOIS.

BUCKLE.

Application filed April 27, 1927. Serial No. 186,922.

My invention relates to buckles and particularly to that type composed of two members, one member pivotally secured upon the other and one member designated as the 5 tongue member, both members jointly operating to clamp between them the strap to which the buckle may be applied.

My invention has for its object the manufacture of a buckle in which the parts composing it are preferably of cast metal and co-operate to hold a strap, with which the buckle is adapted to be used, by clamping the strap at both ends of the buckle.

Referring to the drawings in which similar numerals indicate identical parts—

Figure 1 is a plan view of my buckle applied to a strap. Figure 2 is a section on the line 2—2 of Figure 1. Figure 3 is a plan view of the buckle. Figure 4 is a bottom plan view of Figure 3. Figure 5 is a side elevation of the buckle, and Figure 6 is a side view of one member of the buckle.

The members 1 and 2 are, preferably, cast, the member 1 consisting of side bars 3 and 4 connected by transverse bars 5, 6 and 7, the latter bar having a denticulated outer edge a. The tongue member 2 is formed of side bars 8 and 9 connected by transverse bars 10 and 11. The bar 11 of the tongue member 2, when the buckle is assembled, is located forwardly of the denticulated bar 7 a sufficient distance to provide space for reception of the running part 19 of the strap, and has an upward inclination so as to clamp 35 the strap against the teeth of the bar 7. The side bars 3 and 4 of the member 1 are extended upwardly, intermediate their length, to form bearings 12 and 13 in which are pivotally secured trunnions 14 and 15 integral with the bar 10.

In the manufacture of the member 1 the bearings 12 and 13 are cast open, as shown in Figure 6, to receive the trunnions 14 and 15, and when the latter are in place, I close 45 the bearings by bending the extensions 16 and 17 toward each other over the trunnions and so secure the members 1 and 2 together to form a completed buckle.

In using my buckle the end of a strap is 50 passed around the bar 6 and under the bar 5 back upon itself where it is riveted or otherwise secured. The running part 19 of the strap is passed upwardly between the bar 11 and the denticulated bar 7 and over 55 the bar 10 and then under the bar 5 be-

tween the latter and the fixed part 18 of the strap. It will be noticed that the bar 5, of the part 1, and the bar 10 of the tongue member 2 are substantially in the same horizontal plane as more clearly shown in Figure 5, and the bar 6 is in a lower plane but above the bottom line of the part 1 as shown more clearly in Figure 2, so that it follows that when a strain is brought upon the strap, the part 2 will clamp the running part of 60 the strap against the teeth of the bar 7, and as the strain will seek a straight line, the continued pull, acting upon the bar 11, with an upward stress, will exert its force to rock the part 1 so that the bar 5 will clamp the 65 running part of the strap between the bar 5 and the part 18, the fixed part of the strap, so that the running part 19 is thereby clamped against slipping and is held with a force which is added to by any increase in 70 the strain of the pull.

I have produced a buckle which in continued experiments has proven of great value, particularly when it is used in a position where a positive securing of the strap 80 against slipping is absolutely necessary and which can be relied upon for its efficiency under any conditions.

What I claim is—

1. A buckle, composed of a main member 85 and a tongue member, the main member having bearings projecting upwardly from the sides thereof, the tongue member pivotally mounted in said bearings and extending below and forwardly of the main member to permit the passage of a strap upwardly between the forward ends of said members, a transverse bar on said main member rearwardly of said bearings below the plane thereof and above the plane of the lower 90 side of the main member and to which one end of a strap is to be secured, a transverse bar on the rear of the main member in substantially the plane of said bearings and under which the running part of a strap is 95 to be passed, said tongue member and main member co-operating to clamp the running part of the strap at both ends of the buckle.

2. A buckle, composed of a main member 105 and a tongue member, the main member having bearings projecting upwardly from the sides thereof, a transverse denticulated bar at the forward end of said member, a tongue member pivotally mounted in said bearings 110

and extending below and forwardly of the main member, a transverse bar on the tongue member forwardly of the denticulated bar and co-operating therewith to clamp a strap passed between them, a transverse bar on said main member rearwardly of said bearings and below the plane thereof and above the plane of the lower side of the main member and to which an end of a strap is to be secured, and a transverse bar

on the rear of the main member in substantially the plane of said bearings and under which the running part of a strap is to be passed and clamped simultaneously against the part of the strap secured to the bar rearward of the bearings with and by the clamping action of the tongue member and the denticulated bar. 15

FRED HAUERWAS.
